[57] CLAIM

The ornamental design for a vehicle attached clamp for use with a vehicle frame straightening apparatus, as shown and described.

DESCRIPTION

FIG. 1 is a perspective view of a vehicle attached clamp for use with a vehicle frame straightening apparatus showing my new design installed on an automobile door post, it being understood that the broken lines are for illustrative purposes only and form no part of the claimed design;

FIG. 2 is a top plan view thereof;

FIG. 3 is a rear elevation view thereof;

FIG. 4 is a bottom plan view thereof;

FIG. 5 is a front elevation view thereof;

FIG. 6 is an end elevation view thereof.

FIG. 1

FIG. 2

FIG. 3

FIG. 4

FIG. 5

FIG. 6
